SLUB CATCHING SHUTTLE

Wallace I. Stimpson, Hopedale, Mass., assignor to
Draper Corporation, Hopedale, Mass., a corpora-
tion of Maine

Application May 16, 1933. Serial No. 671,357

5 Claims. (Cl. 139—212)

The present invention pertains to loom shuttles and more particularly relates to filling carrying shuttles having a slub catching device embodied therein.

5 It is not uncommon to provide the conventional filling carrying shuttle, either of the automatically threading or hand threading type, with a so-called slub catching device, which usually consists of a narrow slot through which the running filling passes before it emerges from the eye of the shuttle. The slot is narrow, relative to the diameter of filling being used, and is intended to prevent the passage of imperfections such as thick places in the filling thread, impurities caught in 10 the thread, bunches of lint, or knots or snarled places occasioned by the filling sloughing off the filling carrier. If such imperfections are of a size intended to be held by the slub catcher, and are actually so held, the filling will be broken, 15 thus causing loom stoppage, and preventing the weaving of the imperfections into the cloth.

While an open ended slot is, insofar as I am aware, the simplest and most effective form of slub catcher heretofore devised such arrangement 20 has not proven entirely satisfactory in that it frequently fails to stop even very large imperfections in the filling and permits them to be woven into the cloth. I have found that this failure of operation is due to the fact that when 25 a large imperfection approaches the slub catching slot the filling, together with the imperfection, move laterally out of the open end of the slot, which permits the imperfection to pass on through the shuttle eye and to the cloth. Whether 30 the action of the filling in thus unthreading from the slot is due to centrifugal force occasioned by the swirling or ballooning of the filling as it unwinds from the filling carrier, or is due to a camming contact between the imperfection and the floor or wall of the thread passage, I am not prepared to say. However, I have 35 definitely demonstrated that such unthreading does occur, and it is the object of my invention to provide a slub catcher in the form of a narrow slot, together with means for preventing the filling from unthreading from the slot when a 40 slub, or other imperfection, approaches the slot.

To this end the invention consists in a filling carrying shuttle having a slub catcher comprised 45 of a narrow slot and a thread entrance to the slot adjacent the closed end thereof in which a slub or other imperfection engages, to hold the filling against lateral movement toward the open end of the slot.

50 In the preferred form, I form the slub catching

slot substantially vertically in a wall in the threading block which intersects the path of the running filling, and the thread entrance is constituted by a tapered indentation in the wall at or adjacent the closed end of the slot, although 60 both the slot and the thread entrance may be otherwise constituted.

For detailed disclosure of the preferred embodiment of my invention reference may be had to the accompanying drawing, of which:

Fig. 1 is a fragmentary plan view of the eye 65 end of a shuttle embodying my invention;

Fig. 2 is a vertical sectional view taken approximately on line 2—2 of Fig. 3;

Fig. 3 is an end elevation of the threading 70 block of Fig. 1 removed from the shuttle body, Figs. 2 and 3 being to an enlarged scale; and

Fig. 4 is a view similar to Fig. 2 but showing the action of the slub catcher as the filling passes therethrough.

75 The shuttle shown on the drawing is comprised of the usual wooden body 1 having a cavity 2 therein within which is received a bobbin 3 or other filling carrier. This shuttle is of the automatically threading type, and is accordingly provided with a thread block 4 and a side delivery eye 5.

The threading block 4 is comprised of a floor 6, front and rear walls, 7 and 8 respectively, a horn 9 projecting rearwardly and outwardly from the front wall 7, and a threading scroll 10. The floor 6 inclines upwardly toward the outer end of the threading block, and this floor, together with the walls 7 and 8, form a thread passage which extends longitudinally of the shuttle and through 85 which passage the filling *f* passes before it passes beneath the depending prong 11 and out the eye 5.

A wall 12 extends upwardly from the floor 6 at the outer end of the thread passage and this intersects and is intersected by the path of the running filling. As shown, the wall is approximately vertical, and is formed integrally with the floor and walls of the threading block. The slub catcher, to which my invention more particularly pertains, is conveniently constituted by a narrow slot 13 extending downwardly from the top of the wall 12.

100 The slot 13 is open at the top and extends downwardly and slightly forwardly toward the side eye, in order that the open end thereof may be properly positioned to receive the filling during the threading up process and the bottom, closed end of the slot, where the filling normally runs, is closer to the thread guide passage (not shown) formed on the under side of prong 11. 110

This slab catching slot should be very narrow; in fact, it should not be appreciably wider than the thickness of the filling to be used in the shuttle. Such a construction will not materially interfere with the free passage of the filling as it is payed out from the shuttle, but no slab, knot, or other imperfection substantially larger than the filling can pass through the slot. Accordingly, if the filling can be made to remain in the slot when such an imperfection reaches the wall 10 12 the filling will be broken, and the loom will be stopped in the usual manner, thus permitting the imperfection to be removed rather than move into the cloth.

15 However, as above noted, a simple slot, without more, cannot be depended upon to perform the desired function as the occurrence of an imperfection frequently results in the filling moving laterally (upwardly) out of the slot, which permits the imperfection to pass on out the side eye.

20 I have discovered that the filling can be prevented from becoming unthreaded from the slot by providing the slot with a relatively wide thread entrance in which the leading end of the slab can become wedged. The thread entrance should, of course, be located at the point where the running filling normally enters the slot, which is preferably adjacent the closed end thereof. The shape 25 of the thread entrance may be varied considerably, but it should be such as to effectively hold the filling against movement along the slot once the imperfection has entered the same.

30 The form of thread entrance which I prefer is constituted by an indentation 14 in the wall 12 adjacent the closed end of the slot 13 and intersected by the latter. The indentation shown is 35 of circular outline, approximately twice as wide as the slot, and tapered to the width of the slot in the direction of movement of the filling. Such an indentation may be made with a conventional 40 counter-sink drill, the indentation being formed before the slot 13 is sawed or milled in the wall 12. The action of the indentation in preventing the filling from rising in the slot is illustrated in 45 Fig. 4, wherein the enlargement S is entered into the indentation and held thereby against rising up in the slot.

50 The point of emergence of the filling from the slot may be indented, as at 15, if so desired, this indentation serving merely to round the corners of the slot to prevent chafing of the filling.

Having fully disclosed the preferred embodiment of my invention, I claim:

1. A filling carrying shuttle having a slab

catcher comprised of a narrow open ended slot extending transversely of the path of the filling therethrough, there being a thread entrance to said slot adjacent the closed end only of the latter, which entrance is substantially larger than the said slot, and constitutes means engaging slubs in the filling to prevent the filling from moving laterally out of the slot. 80

2. A filling carrying shuttle having a slab catcher comprised of a narrow open ended slot extending transversely of the path of the filling therethrough, there being a tapered thread entrance to said slot adjacent the closed end only of the latter which tapered entrance constitutes means in which slubs in the filling become wedged, to prevent the filling from moving laterally out of said slot. 85 90

3. A filling carrying shuttle having a wall intersecting the path of the running filling as the latter is payed out from the shuttle, said wall being provided with a relatively narrow slab catching slot through which the running filling normally passes, there being a thread entrance to said slot, which entrance is comprised of a tapered indentation of substantially circular outline formed in the said wall adjacent the closed 100 end of the said slot and intersected by the latter. 95

4. An automatically threading shuttle having a threading block and a side delivery eye, said threading block having a longitudinally extending thread passage and a wall extending upwardly from the floor thereof, said wall being provided with a relatively narrow slab catching slot extending downwardly from the top thereof and through which slot the running filling normally 110 passes, there being a thread entrance to said slot, which entrance is comprised of a relatively wide indentation formed in said wall adjacent the lower end only of the said slot and intersected by the latter. 115

5. An automatically threading shuttle having a threading block and a side delivery eye, said threading block having a longitudinally extending thread passage and a wall extending upwardly from the floor thereof, said wall being provided with a relatively narrow slab catching slot extending downwardly from the top thereof and through which slot the running filling normally passes, there being a thread entrance to said slot, which entrance is comprised of a 120 125 tapered indentation of substantially circular outline formed in said wall adjacent the lower end of the said slot and intersected by the latter. 130
